United States Patent Office.

CHARLES PRATT, OF NEW YORK, N. Y.

Design No. 2,712, dated July 23, 1867.

DESIGN FOR AN OIL-CAN.

The Schedule referred to in these Letters Patent and making part of the same.

TO ALL WHOM IT MAY CONCERN:

Be it known that I, CHARLES PRATT, of the city, county, and State of New York, have produced a new and original Design for Oil-Can, of which—

Figure 1 is a plan or top view, and

Figure 2 a section of the same taken in the line xx , fig. 1.

Similar letters of reference indicate like parts.

The top A of the can is of square form, and has a polygonal raised figure or bead B upon it. The sides of this figure or bead are slightly curved, the outer edges being concave, as shown clearly in fig. 1. Within this polygonal figure or bead there is attached to the top A a handle, C, projecting upward, and having angular ends or corners, as shown in fig. 2.

Having thus described my invention, I claim as new, and desire to secure by Letters Patent—

The raised polygonal figure or bead on the top of an oil-can, to form a new and original design for the same, substantially as shown and described.

CHAS. PRATT.
